UNITED STATES PATENT OFFICE.

JACKSON D. COMSTOCK, OF CHESTER, WEST VIRGINIA, ASSIGNOR TO THE CORD TIRE CORPORATION, OF CHESTER, WEST VIRGINIA, A CORPORATION OF WEST VIRGINIA.

DESIGN FOR A TIRE-CASING.

54,347.

Specification for Design.

Patented Dec. 30, 1919.

Application filed May 16, 1919. Serial No. 297,705. Term of patent 7 years.

To all whom it may concern:

Be it known that I, JACKSON D. COMSTOCK, a citizen of the United States, residing at Chester, in the county of Hancock, in the State of West Virginia, have invented a new, original, and ornamental Design for a Tire-Casing, of which the following is a specification, reference being had to the accompanying drawings, forming a part thereof.

In the drawings, Figure 1 is a plan or edge

view of a portion of a tire, equipped with my tread. Figs. 2 and 3 are cross sections thereof, on the correspondingly numbered lines on Fig. 2.

It is to be understood that the tread is a complete annulus.

I claim:

The ornamental design for a tire casing, substantially as shown in the drawings.

JACKSON D. COMSTOCK.
